UNITED STATES PATENT OFFICE.

FRANK PIRSON, OF KANSAS CITY, MISSOURI.

DESIGN FOR A LAMP BODY.

Application filed October 3, 1921. Serial No. 505,192. Term of patent 3½ years.

To all whom it may concern:

Be it known that I, FRANK PIRSON, a subject of the King of Belgium, residing at 1313 Olive Street, Kansas City, Jackson County, Missouri, have invented a new, original, and ornamental Design for a Lamp Body, of which the following is a specification, reference being had to the accompanying drawing, forming a part thereof.

In the drawing:

Figure 1 represents a perspective view showing two sides of a lamp body embodying my new design.

I claim:

The ornamental design for a lamp body as shown.

FRANK PIRSON.
